WIGELIUS MOTORER, OF STOCKHOLM, SWEDEN.

FUEL-SPRAYER.

1,130,229.

Specification of Letters Patent.

Patented Mar. 2, 1915.

Application filed November 25, 1911. Serial No. 662,280.

To all whom it may concern:

Be it known that I, SVEN GUSTAF WIGELIUS, a subject of the King of Sweden and a citizen of Sweden, residing at 17 5 Kaptensgatan, Stockholm, in the Kingdom of Sweden, have invented certain new and useful Improvements in Fuel-Sprayers, of which the following is a specification.

My invention relates to improvements in 10 devices for spraying fuel into the combustion chambers of internal combustion engines. It provides a device of this character in which the spraying is effected by means of a current of compressed air thus 15 producing a mixture of fine particles of fuel and air.

According to the present invention a 20 valve is provided which is normally held against its seat by a constantly acting pressure such as is produced by the action of a 25 spring or weight, this pressure serving to prevent the valve from being raised off from its seat by any opposing pressure, until it is actuated by the proper means at the 25 proper time.

In my invention the fuel is supplied to 30 the device by means of a suitable pressure pump, not illustrated, in the drawing, since it comprises no part of my invention. This 35 pump is adapted to produce a pressure sufficiently great to overcome the pressure which holds the valve above mentioned normally seated and forces the fuel into the fuel chamber where it comes into contact 45 with a current of compressed air by means of which it is sprayed into the combustion chamber of the engine.

In the drawing annexed hereto and forming 40 a part of this application, and in which I have illustrated one preferred embodiment of my invention, the figure shows a longitudinal cross section view of the preferred form of my invention.

A compressed air chamber *a* leads to the 45 combustion chamber of the engine and has disposed therein in axial alinement, the hollow sleeves *d* and *c*, in the bore of which is disposed the regulating valve spindle *b* co- 50 acting with the valve seat *c'* in the sleeve *c* and a rear annular valve seat *c''* on the sleeve *c* coacting with the vertically reciprocating spindle *d*. The annular mouth *a'* in the channel *a* surrounds the end of the regulating spindle which end is preferably conical in shape. A spring *e* is disposed in the 55

air channel *a* and serves to keep the valve spindle *d* tightly pressed against the valve seat *c''* with sufficient pressure so that the said valve can only be raised from its seat by a counteracting pressure greater than 60 that of the spring *e*. Around the seat *c''* is disposed a fuel chamber *f* and a fuel channel *h* leads thereto said fuel channel being normally closed by a valve *g* which acts as a check valve against pressure in the 65 fuel chamber *f*. The entrance of the fuel to the chamber *f* is controlled by the said check valve *g* which, as before stated, is adapted to be actuated by the pressure of the fuel in the channel *h*, said pressure 70 being produced by any suitable means, such as a pump, so that the fuel is introduced into the chamber *f* and then into the passage *a* at a pressure sufficient to overcome the pressure produced by the compression stroke 75 of the internal combustion engine with which the device is used. It is therefore obvious that the supply of fuel entering the chamber *f* is controlled by the valve *g*.

The check valve *g*, as before set forth, is 80 actuated by fluid pressure, and the spindle *b*, the lower part of which constitutes a valve, is moved by means of a cam or other device not shown, which is actuated and comprises a part of the engine with which 85 the device is used, and so arranged that when the pump forces the fuel from the channel *h* into the fuel chamber *f*, the operation of the spindle *b* is so timed that the spindle *b* will simultaneously be raised and 90 a current of air will rush through the chamber *f* and channel *a* into the cylinder carrying with it the fuel in the chamber *f*. In this way it will be obvious that the fuel is forced through the valve *g* into the air current passing through the channel *a*, when 95 the spindle *b* is raised.

It is to be understood that I do not limit myself to the exact construction and arrangement of parts herein set forth, but 100 may resort to such modifications as fall within the scope of my claims.

I claim:—

1. The combination in a fuel sprayer for 105 internal combustion engines, of a fuel chamber, a fuel valve communicating with said fuel chamber and adapted to be actuated by the fuel supply, an air channel, a valve disposed in said air channel, and communicating with said fuel chamber, and a spindle 110

valve actuated by the engine and adapted to establish communication between the chamber and the combustion chamber of the engine through the valve in said air channel.

2. The combination in a fuel sprayer for internal combustion engines, of a fuel chamber, a fuel valve communicating with said fuel chamber, spring means normally holding said fuel valve in the closed position, said valve being adapted to be actuated by the incoming fuel, a channel having compressed air supplied thereto, a pressure actuated valve disposed in said air channel

and communicating with said fuel chamber, and a reciprocating spindle valve actuated by the engine, and adapted to establish communication between the chamber and the combustion chamber of the engine through the pressure operated valve in said air channel.

In testimony whereof I have affixed my signature in presence of two witnesses:

SVEN GUSTAF WIGELIUS.

Witnesses:
